UNITED STATES PATENT OFFICE.

JOSEPH PEYSER, OF MOUNT VERNON, NEW YORK, ASSIGNOR, BY MESNE ASSIGNMENTS, TO ACKERMANN MANUFACTURING COMPANY, OF WHEELING, WEST VIRGINIA, A CORPORATION OF WEST VIRGINIA.

SEAMING MECHANISM.

1,396,231.

Specification of Letters Patent.

Patented Nov. 8, 1921.

Application filed July 13, 1917, Serial No. 180,270. Renewed February 5, 1921. Serial No. 442,892.

To all whom it may concern:

Be it known that I, JOSEPH PEYSER, a citizen of the United States, and a resident of Mount Vernon, county of Westchester, 5 and State of New York, have invented certain new and useful Improvements in Seaming Mechanism, of which the following is a specification.

The present invention relates generally to 10 can heading machines and has more particularly reference to a double seaming mechanism.

The main objects of this invention are to 15 produce a double seaming mechanism of simple and effective construction and one in which lubrication of the bearings for the seaming rollers may be effectively accomplished.

One feature of the invention resides in the 20 means for bringing the seaming rollers into and out of operative position with respect to the work and consists in utilizing a seaming cam and a carrying member, one of said elements having a relatively rotating movement 25 with respect to the other; and in providing a pivotal support on which the carrying member swings bodily, together with means for effecting the swinging movement of the carrying member from the seaming 30 cam, the swinging movement being controlled by said relative rotating movement so that constant engagement of the cam and the means on the carrying member will automatically effect the bodily swinging movement 35 of the carrying member in either direction from a neutral position.

In the preferred embodiment of the invention, the two seaming rollers are mounted diametrically opposite to each other so 40 that the parts will naturally counter-balance each other without the use of extraneous or additional counterweights.

Another feature of the invention relates 45 to means that admits of a yielding movement of the second operation roller when encountering the extra thickness of metal in line with the longitudinal seam of the body 50 of the can. As here disclosed, the second operation seaming roller has a definite in-and-out movement with respect to the work; and a box cam is utilized for controlling this movement. Between the box cam and the roller, there is a rigid connection but the cam itself is provided with an elastic por-

tion that admits of the roller passing over 55 a raised part on the work. Preferably, sufficient elasticity is imparted to the cam by providing it with a slit in the body thereof. In the preferred embodiment of the invention, two seaming tools or rollers are provided 60 which are arranged diametrically opposite to each other and which move in unison in two directions to and from the work to successively engage it. With these seaming tools is associated a seaming cam; and 65 means is provided for producing a relatively effective circumferential displacement between the tools and cam of one revolution during each cycle of the machine. The cam itself is provided with two sets of cam portions, each set consisting of an active and 70 an inactive portion arranged diametrically opposite to each other; and cam rolls are provided which are also arranged diametrically opposite to each other and substantially 75 in the plane of the seaming tools. In machines of this character, it is understood that the seaming tools and the work holder or chuck have a circumferential displacement with respect to each other amounting to 80 many revolutions, say twenty-five, during each cycle of the machine; and each of the active cam portions is provided with a dwell so that the seaming tool may remain in engagement with the work for a considerable 85 time, preferably for more than one revolution of the work or of the seaming tools as the case may be.

A still further feature of the invention 90 consists in providing a member, usually the carrying member for the tools, with a horizontal portion and with an upstanding annular flange, an annular seaming cam being mounted above said horizontal portion and within the flange and forming, with said elements, an oil reservoir from which oil flows 95 to the bearings of the seaming rollers. The reservoir is preferably supplied with oil from a sleeve that extends through the machine and surrounds the member carrying 100 the chuck.

In the accompanying drawings, the invention is disclosed in two forms: one, in which the work holder is stationary and the seaming tools have a rotating movement 105 around the work and also an in-and-out movement toward and from the work; and the other of which shows the work holder

or chuck rotating and the tools stationary except for the in-and-out movement toward and from the work.

Figure 1 is a vertical sectional view on the irregular lines 1, 1, of Fig. 2, viewing the elements at right angles to the irregular section lines, and shows the invention embodied in a form in which the work holder is stationary.

10 Fig. 2 is a bottom plan view looking in the direction of the arrow 2 of Fig. 1.

Fig. 3 is a vertical sectional view showing a form of the invention in which the work holder rotates.

15 Referring to Figs. 1 and 2, 1 indicates a chuck or work holder mounted upon a shaft 2, the work holder being, in this instance, stationary. It is, of course, understood that there is a similar member below that co-
20 operates with chuck 1 but which is not shown in this instance. 3 indicates a carrying member, here shown as being provided with a horizontal portion 4 and an upstanding annular flange 5 surrounding the same.
25 This carrying member is supported on a pivotal member 6 carried by the lower end 7 of the member 8. In this instance, the work holder and the carrier are given a relatively circumferential displacement with
30 respect to each other, amounting to many revolutions during each cycle of the machine, by imparting a suitable rotating motion to the member 8 in a manner well understood in the art. Since the carrying member 3 is pivotally supported on the member 8, it follows that it partakes of the rotating motion of said member. 9 indicates a seaming cam, of the inclosed or box type, mounted above the horizontal portion
35 4 of the member 3 and within the upstanding flange 5. The primary function of the seaming cam is to impart an in-and-out movement to the seaming tools; and to this end, said seaming cam and said carrying member have a relatively rotating movement with respect to each other, the effective circumferential displacement of said elements during each cycle of the machine being equal
40 to one revolution. Since the carrying member 3 rotates with the member 8, the seaming cam is, in the present instance, given, during each cycle of the machine, a number of revolutions slightly less than that of the carrying member 3. It will be understood
45 that the differential gearing for producing these results form no part of the present invention and need merely be referred to since they are exceedingly well understood in the art and may, of course, take many forms.
50

55 60 The seaming cam 9 is mounted on a sleeve 10, through which it receives its rotating movement, by means of a key 11; and the carrying member 3 is held against the portion 7 by means of a gland 12, or in any other suitable manner that will not inter-

fer with its swinging movement on pivot 6. 13 and 14 indicate two seaming rollers, 13 being the first, and 14 the second, operation roll. Each of these rollers is mounted in a bifurcated arm 15 having suitable bearings 16, said arm 14 being slidably mounted on the carrying member 3 by means of a guide 17 extending into a slot 18 and held in position by means of a stud bolt 19. It will be apparent that, by loosening the set screw 19 and adjusting the bifurcated member 14, the seaming roller will be adjusted toward and from the work holder to accommodate cans of different size. The seaming rollers 13 and 14 are mounted beneath the carrying member 3 and substantially directly above the same are the cam rollers 20 that extend into the groove of the seaming cam 9. It will be noted that the seaming rollers 13 and 14 are diametrically opposite to each other 80 and that the cam rollers 20 are disposed, in the present instance, in the same manner. The seaming cam 9 is provided with two sets of cam portions, each set consisting of an active portion 21, 22 and an inactive portion 23, 24, the arrangement being such that the active and the inactive portions are diametrically opposite to each other. The cam 9 is further provided with neutral portions 25 and 26 for the purpose of maintaining the seaming rollers, for a short period, in a neutral position substantially midway of their inner and outer positions. Each active portion 21 and 22 is provided with a dwell 27 for purposes to be hereinafter described. 28 indicates a slit in the body of the cam adjacent to the active portion controlling the second operation seaming roll, thereby imparting a certain amount of elasticity to the wall of the cam so that the second operation 100 roller, when passing over the extra thickness of metal in line with the longitudinal seam of the body of the can, may yield slightly; and, in order to admit of this, the active portion 24 should have a slight clearance at 29.

105 The can to be seamed is inserted in the machine, in any customary manner, between the chuck and its coöperating element (not shown), this taking place when the seaming rollers are occupying the neutral position indicated in Fig. 2. The rotation of the seaming cam 9, in the direction indicated by the arrow, will now cause cam roller 20 of the first operation seaming roll to engage 115 with the active portion 21 of the cam, cam roller 20 of the second operation seaming roller 14 engaging, at the same time, with the inactive portion 23. Since there is a rigid connection from the cam rollers to the carrying member 3 and from the carrying member to the seaming rollers, it is evident that said carrying member 3 will swing bodily on its pivot 6 thereby causing the first operation roller 13 to engage with the work 120 125 130

to perform the initial curling operation of the cover and can. Owing to the dwell 27, the seaming rollers will rotate around the work for more than one revolution, preferably two, while the first operation roller is in working position, in fixed relation to center of can, thereby insuring a uniform effective curling operation. Continued rotation of seaming cam 9 will now bring cam roller 20 of the first operation seaming roller into the inactive portion 24 of the cam and cam roller 20 of the second seaming operation roller 14 into the active portion 22 of seaming cam 9. This will cause the carrying member 3 to move bodily around its pivot 6 in a direction opposite to that previously noted; and will move the first operation seaming roller outwardly and the second operation seaming roller inwardly into working position. The seaming roller 14 remains in engagement with the work, preferably during several revolutions of the carrying member 3, owing to the presence of dwell 27, previously noted; but, in addition to this, said seaming roller 14 will be permitted to move outwardly when passing over the extra thickness of metal in line with the longitudinal seam of the body of the can by reason of the elastic or resilient wall 30 in cam 9 produced by slit 28. It will be understood that as seaming roller 14 moves outwardly to a slight extent, when in the position described, seaming roller 13 must move inwardly to the same extent and cam rollers 35 20 on both seaming rollers being rigidly connected therewith, the same movement will be imparted to them. As stated, to compensate for this, the wall of the cam yields on account of slit 28, and cam roller 20 on 40 seaming roller 13 is permitted because of the clearance 29 to move inwardly to a slight extent. This operation has been described in terms of movement of the seaming rollers but it will, of course, be understood that 45 what actually takes place is a bodily swinging movement on the part of the carrying member 3 around pivot 6. After the second operation seaming roller has completed its work, the parts will again assume the position shown in Fig. 1, and the finished can is then removed and another can substituted.

In the foregoing description of the operation of the machine, the action which takes place during one half revolution of the cam 55 9 only has been set forth. It will be apparent that during the remaining half of the revolution the cam roller 20 of the first seaming roller 13 will engage the inactive portion 23 and the active portion 22, while 60 the cam roller 20 of the second seaming roller 14 will engage the active portion 21 and the inactive portion 24 of cam 9, and that no seaming operation takes place during said second half revolution.

65 The advantage of the construction dis-

closed will be apparent when it is pointed out that the elements of the carrying member 3 are in perfect balance due to the position of the tools and rollers at diametrically opposite points. This renders unnecessary 70 extraneous balancing elements that would increase the weight of the rotating parts. The dwell 27, which admits of the tools remaining in fixed relation in engagement with the work for a considerable period, is also of 75 importance and is far better than constructions utilizing a constantly shifting eccentric in which the innermost working position of the seaming roller is practically only a momentary one. Also, the arrangement of 80 the seaming rollers on opposite sides, instead of in clusters or groups, is an advantage in that it gives ample time for each operation during a cycle of the machine. The elastic wall, caused by the slit 28, of the seaming 85 cam 9 has already been explained but it should be stated that after passing the high point due to side seam of can, the seaming roller will immediately assume its innermost position and will continue to press the parts 90 home. A very rigid construction of all the parts is, of course, an advantage since the whole object of the device is to apply pressure of the requisite character to sheet metal articles.

95 The construction whereby all of these advantages are obtained is simple in form; and, moreover, lends itself very readily to an easy method of lubrication. As here shown, the horizontal portion 4 of the carrying member 3 and the upstanding annular wall 5 together with the periphery of the seaming cam 9 form, in effect, an oil reservoir. This reservoir may be conveniently fed from the upper part of the machine, the oil coming down inside sleeve 10 and flowing down through passage 30 and between the carrying member 3 and cam 9, thus reaching the reservoir. 31 indicates a passage 100 through the carrying member 3 permitting the oil to flow to the under side thereof and thence to a channel 32, preferably centrally disposed in the support for the seaming roller; and thence outwardly through a branch passage 33 to bearing 16 of the seaming roller. It will be seen that by this 105 method of lubrication an ample reserve supply is always available in the reservoir.

110 Referring now to Fig. 3, it will be understood that this view is merely included to 115 show how the same invention may be utilized in a machine in which the work rotates and in which, as a consequence, the seaming rollers have a simple in-and-out movement.

120 In this form of the invention, it will be understood that the relatively circumferential displacement of the seaming cam 9 with reference to the carrying member 3 is effected by rotating said seaming cam 9 once 130

during each cycle of the machine by means of sleeve 10.

Since the carrying member 3 does not rotate in this form of the invention, it is possible to pivotally support same on the pivot 35 that extends from the framing of the machine. With this construction, the operation of the machine is, so far as the parts relating to the invention are concerned, precisely 10 the same as that previously described.

I claim:

1. Seaming mechanism comprising: a seaming cam, a carrying member, one of said elements having a relative rotating movement with respect to the other, two seaming tools mounted diametrically opposite to each other on said carrying member, and means for successively moving the two seaming tools toward and away from the work including a pivotal support circumferentially intermediate the two seaming tools on which the carrying member swings bodily, and connections between the cam and carrying member for effecting a swinging movement of the latter on its pivotal support by the relative rotating movement of said cam and carrying member.

2. Seaming mechanism comprising: a seam cam, a carrying member, one of said elements having a relative rotating movement with respect to the other, producing an effective circumferential displacement of said elements with respect to each other of one revolution to each cycle of the machine, two seaming tools mounted diametrically opposite to each other on said carrying member, a pivotal support circumferentially intermediate the two seaming tools on which the carrying member swings bodily, two sets 40 of cam portions on said cam for successively actuating each seaming tool, each set consisting of an active and an inactive portion diametrically opposite to each other, and cam rolls diametrically opposite each other and substantially in vertical line with the seaming tools.

3. Seaming mechanism comprising: a seaming cam, a carrying member, one of said elements having a relative rotating movement with respect to the other, producing an effective circumferential displacement of said elements with respect to each other of one revolution to each cycle of the machine, two seaming tools mounted diametrically opposite to each other on said carrying member, a pivotal support circumferentially intermediate the two seaming tools on which the carrying member swings bodily, two sets of cam portions on said cam for successively actuating each seaming tool, each set consisting of an active and an inactive portion diametrically opposite to each other, one of said active cam portions being elastic to permit its corresponding seaming tool to pass 60 over a raised portion on the work, and cam

rolls diametrically opposite each other and substantially in vertical line with the seaming tools.

4. Seaming mechanism comprising: a seaming cam, a carrying member, one of said elements having a relative rotating movement with respect to the other, producing an effective circumferential displacement of said elements with respect to each other of one revolution to each cycle of the machine, 70 two seaming tools mounted diametrically opposite to each other on said carrying member, a pivotal support circumferentially intermediate the two seaming tools on which the carrying member swings bodily, two sets of 80 cam portions on said cam for successively actuating each seaming tool, each set consisting of an active and an inactive portion diametrically opposite to each other, said active portion having a dwell, and cam rolls diametrically opposite each other and substantially in vertical line with the seaming tools.

5. Seaming mechanism comprising: a seaming tool having a definite in-and-out movement, a box cam controlling said movement, connections between said cam and tool, and an elastic portion on said cam formed by a slit in the body thereof to permit the tool to pass over a raised portion on the work.

6. Seaming mechanism comprising: a member having a horizontal portion and an upstanding annular flange, an annular seaming cam above said horizontal portion and within said flange forming, with said elements, an oil reservoir, seaming rollers, and lubricating means for the bearings of the rollers connected with said reservoir.

7. Seaming mechanism comprising: a carrying member having a horizontal portion and an upstanding annular flange, an annular seaming cam above said horizontal portion and within said flange forming, with said elements, an oil reservoir, seaming rollers on the carrying member, means actuating 105 the seaming rollers from the cam, and lubricating means for the bearings of the rollers connected with said reservoir.

8. Seaming mechanism comprising: a member having a horizontal portion and an upstanding annular flange, an annular seaming cam above said horizontal portion and within said flange forming, with said elements, an oil reservoir, seaming rollers, lubricating means for the bearings of the rollers connected with said reservoir, and means for supplying oil to said reservoir.

9. Seaming mechanism comprising: a carrying member having a horizontal portion and an upstanding annular flange, an annular seaming cam above said horizontal portion and within said flange forming, with said elements, an oil reservoir, seaming rollers on the carrying member, means actuating the seaming rollers from the cam, lubricat- 130

ing means for the bearings of the rollers connected with said reservoir, and means for supplying oil to said reservoir.

10. Seaming mechanism comprising: a carrying member having a horizontal portion and an upstanding annular flange, an annular seaming cam above said horizontal portion and within said flange forming, with said elements, an oil reservoir, seaming

rollers on the carrying member, a sleeve within said cam, means for supplying oil to said reservoir from said sleeve, and lubricating means for the bearings of said rollers connected with said reservoir.

Signed at Mt. Vernon, in the county of 15 Westchester and State of New York, this 12th day of July, 1917.

JOSEPH PEYSER.
